UNITED STATES PATENT OFFICE

156,788

COMBINED COMB HOLDER AND TRAY

Bernard Ulvad, Leominster, Mass., assignor to Foster Grant Co., Inc., Leominster, Mass., a corporation of Massachusetts

Application March 26, 1949, Serial No. 1,650

Term of patent 14 years

(Cl. D86—10)

To all whom it may concern:

Be it known that I, Bernard Ulvad, a citizen of the United States, residing at Leominster, in the county of Worcester, State of Massachusetts, have invented a new, original, and ornamental Design for a Combined Comb Holder and Tray, of which the following is a specification, reference being had to the accompanying drawing, forming part thereof, in which:

Figure 1 is a top plan view of the combined comb holder and tray embodying my design;

Fig. 2 is a front elevation thereof; and,

Fig. 3 is an end elevation.

I claim:

The ornamental design for a combined comb holder and tray, substantially as shown.

BERNARD ULVAD.
